UNITED STATES PATENT OFFICE

2,545,537

MEANS FOR INTERCEPTING THE ESCAPE
OF ASH TO THE ATMOSPHERE

Edward C. Addison, Stone Harbor, N. J.

Application November 20, 1946, Serial No. 711,094

5 Claims. (Cl. 183—31)

1

The principal object of the present invention is to oppose or prevent the escape into the atmosphere of objectionable solid products of combustion in powdered form derived from powdered fuel; and second, to deliver into the atmosphere gaseous products of the combustion of powdered fuel, and collect solid particles of the residue of the combustion.

Other objects of the present invention will appear from the following description at the end of which the invention will be claimed.

Generally stated, the invention consists in opposing or preventing the escape to the atmosphere of powdered ash resulting from the combustion of powdered fuel, which comprises a screen through which the ashes from the solid fuel may not pass and by which they are entrained, a water spray for washing solid particles from the screen, and an offtake to the atmosphere directed to the outlet of the screen.

The invention also comprises the improvements to be presently described and finally claimed.

In the following description reference will be made to the accompanying drawing forming part hereof and in which,

Figure 1 is an elevational view.

Fig. 2 is a top or plan view, and

Fig. 3 is a detail of construction taken on the line 3—3 of Fig. 1.

Referring to the drawing, in the collecting of fly ash, soot, or light, fluffy, dusty ash from either pulverized fuel boilers or spreader type stokers, a vacuum ash conveyor 1 collects this material from the various collecting points and discharges the material into a tile silo 2 where it is collected until it is carted away in trucks or railroad cars. In order to convey this material by means of a vacuum it is necessary for large amounts of air to be carried in the pipe 1 along with the material to be conveyed. The air enters the receiver 3 where it is desirous to separate the material from the air, i. e., the material discharges into the silo 2 and the air passes out of the receiver 3 into an air washer 4. By installing plain water sprays 5 in the air washer 4 the force of this air mixed with the fly ash carried over carries the water from the spray on with it. In other words, there is not sufficient resistance in the water spray to knock down the fly ash in the air. In order to accomplish this the spray pipe 5' is installed, in the bottom of which is provided holes spaced at approximately 1 inch centers. From these spray pipes 5' is hung a section of flexible heavy wire spiral screen 7, which makes it necessary for the air and dust to go through this screen 7 which is

2

covered with a complete body of water. In other words, the particles in the air hit the screen 7 and the water keeps the screen clean by washing the particles off the screen and draining them into the sump cleared through the drain pipe 9. 10 and 8 are connections for introducing and withdrawing water into and out of the receiver 3. From the receiver 3, 12 indicates an offtake to the atmosphere.

10 It will be obvious to those skilled in the art to which the invention relates that modifications may be made in details of construction or arrangement without departing from the spirit of the invention.

15 I claim:

1. An apparatus for separating dust, fly ash and other such light-weight residue products of combustion from a conveying stream of a gaseous medium comprising a main collection chamber 20 for receiving the heavier products of combustion, a separator operatively associated with said main chamber having an intake opening in communication with a delivery conduit for said products of combustion a discharge conduit for said separator 25 open to atmosphere, said discharge conduit including a laterally offset portion having a bottom wall which slopes downwardly and away from the central axis of said separator, screen means disposed within said offset portion of the discharge conduit for intercepting passage of the light-weight products of combustion to atmosphere by way of said discharge conduit while permitting free passage therethrough of said conveying stream of the gaseous medium, and means for 30 continuously flowing water over said screen means to wash the same free of the intercepted products of combustion, said water being directed by the sloping wall of the offset portion of the discharge conduit to a point external of the separator.

40 2. An apparatus for separating dust, fly-ash and other such light-weight residue products of combustion from a conveying stream of a gaseous medium comprising a conduit system having its outer end open to atmosphere and through which the products of combustion are conveyed by said gaseous stream, a centrifugal separator connected in said conduit system for initially separating from said stream the heavier products of combustion, a main collecting chamber operatively 45 associated with said separator for receiving said heavier products discharged by gravity from said separator, said conduit system including therein a conduit section inclined downwardly and outwardly from the discharged end of said separator, 50 a screen interposed in said inclined section of the

conduit system for intercepting passage to atmosphere of the light-weight products of combustion carried through the separator, and spray means for continuously flowing water over said screen to wash the same free of the intercepted products of combustion and convey them to a point of collection external of said main collector.

3. An apparatus for separating dust, fly-ash and other such light-weight residue products of combustion from a conveying stream of a gaseous medium comprising a conduit system having its outer end open to atmosphere and through which the products of combustion are conveyed by said gaseous stream, a centrifugal separator connected in said conduit system for initially separating from said stream the heavier products of combustion, a main collecting chamber operatively associated with said separator for receiving said heavier products discharged by gravity from said separator, a screen interposed in said conduit at a point external of said separator to intercept passage to atmosphere of the light-weight products of combustion carried through the separator by said gaseous stream, and spray means for flowing water over the full surface of said screen to effect complete separation of the intercepted products of combustion from the gaseous stream, the section of the conduit in which said screen is interposed being arranged to facilitate flow of the wetted products of combustion by gravity to a point external of the separator and said main collecting chamber.

4. An apparatus for separating dust, fly-ash and other such light-weight residue products of combustion from a gaseous conveying stream comprising a centrifugal separator having an outlet in communication with a discharge conduit open to atmosphere, said conduit having an intermediate section which slopes downwardly to one side of the separator outlet, an interceptor

screen disposed in said downwardly sloping section of the discharge conduit for intercepting the passage of light-weight particles carried through said separator by said gaseous stream, spray means for continuously flowing water over the full surface of said screen for washing the latter free of the intercepted particles while permitting discharge of the gaseous stream to atmosphere, and means for effecting gravity flow of the wetted products of combustion intercepted by said stream from said sloping section of the conduit to a point of collection removed from said separator.

5. In an apparatus as defined in claim 4 wherein said interceptor screen is in the form of a vertically disposed member extending transversely of the discharge conduit open to atmosphere and wherein said spray means is in the form of a perforated water tube secured to and extending longitudinally along the upper edge of said vertically disposed screen member.

EDWARD C. ADDISON.
